(57) **CLAIM**

The ornamental design for a spa loudspeaker housing, as shown and described.

DESCRIPTION

FIG. 1 is a front right top perspective view of a spa loudspeaker housing according to the present invention.

FIG. 2 is a front view thereof.

FIG. 3 is a bottom view thereof.

FIG. 4 is top view thereof.

FIG. 5 is a right side view thereof, the left side view being a mirror image thereof; and,

FIG. 6 is a rear view thereof.

The broken lines illustrate portions of the spa loudspeaker housing that form no part of the claimed design.

1 Claim, 5 Drawing Sheets
